UNITED STATES PATENT OFFICE.

WILLIAM A. HARRIS, OF GREENVILLE, SOUTH CAROLINA.

HOEING-MACHINE.

No. 873,543.

Specification of Letters Patent.

Patented Dec. 10, 1907.

Application filed March 21, 1907. Serial No. 363,613.

To all whom it may concern:

Be it known that I, WILLIAM A. HARRIS, a citizen of the United States, and a resident of Greenville, in the county of Greenville and 5 State of South Carolina, have invented certain new and useful Improvements in Hoeing-Machines, of which the following is a specification.

This invention is an improvement in hoeing machines specially designed for chopping cotton, and has for an object to provide a novel construction of machine in which the several parts are capable of operation and adjustment in such manner as to effectually 10 hoe the cotton; and the invention consists in certain novel constructions and combinations of parts, as will be hereinafter described and claimed.

In the drawings Figure 1 is a top plan 20 view of a machine embodying my invention. Fig. 2 is a vertical longitudinal section on about line 2—2 of Fig. 1. Fig. 3 is a cross-section on about line 3—3 of Fig. 1. Fig. 4 is a detail perspective view illustrating the 25 carrier frame, the hoeing frame and portions of the main frame, the cultivating frame and parts immediately associated therewith. Fig. 5 is a detail section on about line 5—5 of Fig. 1 illustrating the countershaft and its 30 connection with the main frame and the hoeing frame. Fig. 6 is a detail perspective view of the carrier frame. Fig. 7 is a detail perspective view, parts being broken away 35 showing the hoeing shaft and the hoes set adjustably thereon, and Fig. 8 is a detail section of the hub portion of the hoe set shown in Fig. 7.

In carrying out my invention I provide a main frame A to which the shafts B¹⁰ may be 40 secured and in this main frame I journal a drive shaft B which may be driven in any suitable manner, preferably by means of a wheel B' secured thereto, the opposite wheel B² being loose on the shaft to facilitate turning 45 the machine. On this drive shaft B, I pivot at its rear end what for convenience of reference I term a carrier frame C, which frame is slidable along the drive shaft so it and the parts carried thereby may be adjust- 50 ed to any desired position, and it also rocks on the drive shaft so that one end of the carrier frame and the parts carried thereby may be raised and lowered in the manner more fully described hereinafter. This carrier 55 frame C supports at its rear end the cultivating plows D and the lister shoes E, the beams

F carrying the said parts being pivoted at their front ends in connection with the carrier frame and provided with a lever F' whose detent F² engages with a rack F³ on the 60 carrier frame whereby to secure the hoes in any desired adjustment up or down, independent of the rocking of the carrier frame upon the drive shaft. The carrier frame may be shifted along the drive shaft to any 65 desired position in order to properly aline the hoeing devices presently described with the row to be hoed by means of the lever H pivoted at H' between its ends to the bracket H² on the main frame and at its lower end to 70 the carrier frame and having a detent H³ engaging with the rack segment H⁴ on the said bracket for holding the lever and the carrier frame slidably in any desired position.

The hoeing frame I is pivoted at one edge 75 I' on an axis approximately in line with the direction of motion of the machine and at its opposite edge has bearings I² for the supporting shaft of the chopping hoes. In pivoting the frame I at I' it is preferred to mount 80 it in bearings at I³ in the carrier frame, said bearings I³ being arranged near the rear end of the hoe or chopper frame and the said chopper frame in rear of the bearings I³ having bearings at J' for the rear end of a countershaft J, the said shaft journaling at its 85 front end in a bearing J³ in the hoeing frame, a boss J⁴ on the hoeing frame journaling in the carrier frame and forming a pivot for the rear end of the chopper frame in connection 90 with the carrier frame, as will be understood from the drawings. By the described construction it will be noticed the chopper frame may be raised and lowered at its swinging edge which carries the hoe supporting shaft 95 and the rocking of the chopper frame is accomplished by means of the lever K projecting upwardly from the chopper frame and having a detent pawl K' engaging with a rack K² mounted on the carrier frame so the 100 chopper frame may be rocked to adjust its hoes up and down and secure them at any desired level.

At its front end the chopper frame I is pivotally and slidably supported on a trans- 105 verse track-way L, one end of which is pivoted at L' in connection with the main frame and its other end is movable up and down by means of a bell-crank lever L² pivoted at L³ to the main frame and having a forwardly 110 projecting arm connected with the movable end of the track-way L and an upwardly pro-

jecting handle arm having a detent pawl L^4 5 engaging with the rack L^5 on the main frame. By this means the track-way may be raised and lowered at one end to any desired point in order to adjust the front end of the chopper frame at the desired height from the ground to properly level the hoes, and this is especially useful in adapting the machine to the draft animals hitched to the machine.

10 By mounting the front end of the chopper frame to slide along the track-way I provide for the lateral movement of the carrier frame and the chopping devices carried thereby in bringing the chopping devices in alinement with the row as before referred to. In mounting the front end of the chopper frame in the track-way I prefer to pivot said frame at L^6 in a block L^7 , which is slidable in a suitable groove L^8 in the track-way L , as shown 15 in the drawings.

By the described construction it will be noticed I have provided for shifting the carrier frame along the drive shaft, for rocking the chopper frame relatively to the carrier frame, 20 for raising and lowering the chopper frame to conform to the team and also means for adjusting the cultivating devices which are mounted on the carrier frame independently of the said frame, together with means 25 for securing the different parts in any desired adjustment, and for operating the chopping hoes.

In leveling the hoeing frame it will be noticed that as the said frame rocks on the axle 30 and as the main frame also rocks on the axle in hitching a large or a small animal to it, it is only necessary in securing the desired leveling of the hoeing frame to raise and lower its front end and this may be readily accomplished by the devices for adjusting the trackway as before described.

On the countershaft J , I mount the pinion j which may be adjusted along the countershaft in order to set it into mesh with 35 any desired circle M' of teeth on the master gear M in order to vary the speed at which the hoe is operated. This master gear M is keyed to the drive shaft and is journaled to the carrier frame so it moves therewith along 40 the drive shaft and is maintained in mesh with the pinion j in the different adjustments of the carrier frame along the drive shaft. On the countershaft J , I also mount a pulley j' connected by a belt N with a pulley N' yieldingly mounted on the hoeing shaft. This pulley N' is connected by a 45 spring N^2 with the hoeing shaft and a pin N^3 on the hoeing shaft engages a shoulder N^4 on the pulley N' so the hoeing shaft may yield 50 slightly when it strikes a stone or other obstruction, in order to prevent unnecessary damage and wear and tear on the machine.

A belt tightener has a pulley O bearing 55 against the belt N and spring pressed normally against the said belt to maintain its

tension so the belt will properly drive the hoeing shaft. This pulley O is carried on the end of an arm O' of a shaft O^2 journaled in bearings on the hoeing frame and said shaft O^2 is provided with a handle arm O^3 by which the belt tightener may be released against the action of the spring O^4 which operates upon its arm O' , as before described. By this construction the operation of the hoe may be stopped whenever desired in order to bring the hoes to cut at the desired points in the row.

The supporting shaft P for the hoes is journaled at the swinging edge of the hoeing frame and is provided with two sets of hoes. One 80 set of hoes is provided with the arms Q supporting the blades and rakes and the other set with arms R supporting its blades and rakes. The arms Q have the hub Q' mounted on the shaft P and secured in any suitable 85 manner, it may be by a clamping screw as shown, so the arm may be adjusted readily on the shaft in order to set its hoeing devices nearer to or farther from the hoes of the other set in varying the cut as may be desired. 90

The arms Q are provided at their outer ends with the blades Q^2 and in advance thereof with the rakes Q^3 , the latter being held on bars Q^4 which are adjustable in a longitudinal direction across their arms Q , crossing the same in a diagonal direction and being set in a recess in the arms Q and secured by a set screw Q^5 passing through a slot Q^6 in the bar Q^4 so the rakes may be set in and out relatively to their respective blades. By this 100 construction the rakes may be set in and out and when adjusted outwardly beyond the edges of the hoe blades they will loosen up the soil before the hoes strike, and when on a level with the hoe the rakes will operate to remove stones or other obstructions. These 105 rakes it will be noticed operate in advance of their respective hoes and serve as guards therefor in the operation of the invention.

The other hoe section has its arms R provided with blades and rakes similar to those described in connection with the arms Q except one of the hoe blades r on the arm R is adjustable by means of slots R' therein to receive the screws connecting it to its arm R . 110 so said blade may be adjusted in the direction of travel of the machine in order that it may be set rearwardly whenever desired in order to increase the cutting capacity of the hoes. 115

It is well understood by those familiar with the cultivation of cotton that the stand of cotton left in the hoed row is usually only about one inch and by adjusting the hoe blade r rearwardly so it will increase the cutting capacity of the hoe to the extent of the 120 adjustment of said blade r , I practically double the cutting capacity of the machine and am able to secure six different widths of cut with the three speeds. Thus, for instance, when running at the highest speed, the hoes 125 130

when adjusted close together and the blade r set in its foremost position, will cut a space of ten inches between cotton and leave the latter standing about one inch. If now the 5 blade r be adjusted rearwardly, say two inches, it will increase the cut space to twelve inches instead of ten and in operation the excess on one of the hoes will cut out every other bunch, which would otherwise be left 10 standing, so the slight addition to the lengths of the hoes resulting from this adjustment of the blade r enables me to practically double the capacity of the machine. In other words, it permits me to double the space between 15 stands by cutting out every other stand left by the operation of the other parts of the hoeing devices.

The hoe sections are preferably adjustable relatively in the direction of travel of the 20 machine and this is preferably effected by making the hub R^2 of the arms R movable longitudinally along the shaft P to which it is keyed and to groove the said hub R^2 at R^3 to facilitate its connection with the pitman 25 S' connecting it with a crank arm S^3 on an upright shaft S^3 journaled in bearings on the hoeing frame and having a handle lever S^4 whose detent pawl S^5 engages with a rack S^6 mounted on the hoeing frame. By this construction 30 the hoeing section having the arms R may be adjusted relatively to the section having the arms Q in the direction of motion of the machine so as to increase the length of the cut of the hoeing devices of one section 35 operating in rear of the hoeing device of the other section and partially overlapping the same, as shown in the drawing. It will be noticed that one of the hoeing sections may 40 be adjusted rotarily on the shaft, as before described in order to set its hoes nearer to or further from the hoes of the succeeding section and this is advantageous in securing a regulation of the cut as when the blades of the succeeding hoeing section operate closely 45 behind those of the preceding section the cut is greater than if the rear hoes be set rotarily further from the advance hoes, as the advance movement of the machine will decrease the cut relatively to the distance the 50 hoes of one set are set in rear of those of the other set.

The provision in a hoeing machine of a revolving hoe having two sets of hoeing devices, one set being adjustable relatively to 55 the other in the direction of the axis of the revolving hoe is an important feature of my invention, both when considered alone and when considered in connection with the mechanism for operating the hoe at varying 60 speeds relatively to the travel of the machine, as thereby I am able to conveniently vary the cut of the machine by shifting the hoeing sections of the hoeing devices to produce a wider or narrower cut and I am also 65 able to secure any desired cut at any desired

speed of the hoe without removing the hoeing blades and substituting therefor blades of other lengths. Thus when the machine is being operated at a high or low speed or an intermediate speed by the adjustment of the 70 pinion j into mesh with any desired row of teeth on the master wheel M the set of hoeing devices movable along the supporting shaft P may be adjusted toward or from the other set in such manner as to secure any desired 75 cut to leave any desired stand of cotton in the drill row without necessitating any change of the hoeing blades. By adjusting the blade having the slots R' as before described to the rear, I may increase the cutting capacity of the hoe to such an extent as 80 to double such capacity in the use of the invention.

In the operation of the invention by one skilled in the hoeing of cotton it will be found 85 that various adjustments of the different parts will facilitate the hoeing of the cotton in such manner as to produce almost if not quite, as good results as those secured by hand by a person experienced in hoeing cotton, and results much superior to the ordinary chopping operation as commonly practiced. In the operation of the machine the driver on the seat S with his feet on the foot-rests S^{11} and S^{12} can conveniently manipulate 90 the several levers for operating the different parts, as before described, and will be in full view of the cotton row and of the hoeing devices so the operation of the same may be governed by the various devices and the 95 movements of the different parts, as before described.

The end of the axle or drive shaft supporting the loose wheel is preferably extended outwardly beyond the main frame so the 105 said wheel may be adjusted outwardly thereon as indicated in dotted lines Fig. 1 to increase the gage of the machine, the lateral adjustment of the hoeing devices permitting the centering or alining thereof in all gages. 110

I claim—

1. A machine substantially as herein described, comprising a main frame, a drive shaft, a carrier frame slideable along and rockable on the drive shaft, a master gear keyed 115 to the drive shaft and movable with the carrier frame along said shaft, a hoeing frame journaled at one edge to the carrier frame and movable up and down at its other edge and provided at said edge with hoeing devices and with a shaft supporting the same, a 120 countershaft having a pinion meshing with the master gear, a belt connecting the said countershaft with the shaft of the hoeing devices, a trackway in which the front end of 125 the hoeing frame is movable longitudinally, said trackway extending transversely of the main frame and pivoted at one end in connection therewith, means for adjusting the other end of the trackway up and down rela- 130

tive to the main frame, means for shifting the carrier frame along the drive shaft, and intermediate devices between the chopping frame and the carrier frame for raising and 5 lowering the movable end of the hoeing frame, substantially as set forth.

2. The combination of the drive shaft, a carrier frame thereon, a hoeing frame pivoted at one edge and movable up and down 10 at its other edge whereby it may be set toward and from the ground hoeing, devices carried at the movable edge of the hoeing frame, and a vertically adjustable support for the front edge of the hoeing frame whereby 15 it may be set up and down for leveling said frame in the use of the implement, and means for raising and lowering the hoeing devices independent of the leveling adjustment at the front edge of the hoeing frame, substantially as set forth.

3. In a machine substantially as described, a hoeing frame pivoted at one edge on an axis in the direction of motion of the machine whereby its other edge may be raised 25 and lowered with respect to the ground surface, and intermediate devices between said hoeing frame and main frame whereby the hoeing devices may be leveled with regard to the ground surface, substantially as set forth.

4. The combination substantially as herein described of the main frame, a drive shaft, a carrier frame sliding along and rocking on the drive shaft, hoeing devices supported by the carrier frame, means intermediate the 35 drive shaft and hoeing devices for operating the latter, means for moving the carrier frame along the drive shaft, and means for rocking said frame on the drive shaft, substantially as set forth.

5. The combination of the supporting shaft, two sets of hoes having their carriers mounted on said shaft and one set being movable along the shaft independent of the other set whereby to vary the width of the 45 cut, and means for sliding the movable set to and securing it in any desired position.

6. A hoeing machine comprising a supporting shaft, a pair of hoe carriers mounted on said shaft, one of said carriers being movable 50 along the shaft independent of the other carrier to vary the width of the cut and means whereby such carrier may be adjusted along its shaft while the implement is in motion.

7. In a machine substantially as described, 55 the combination of a main frame, a drive shaft, a carrier frame slideable along and rocking on the drive shaft, cultivating devices supported at the rear end of the carrier frame, a hoeing frame having its rear end 60 pivotally mounted at one edge in the carrier frame, a bar extending transversely of the main frame in advance of the hoeing frame and pivoted at one end to the main frame and having between its ends a track-way for 65 the front end of the hoeing frame, means for

adjusting the movable end of said bar up and down relative to the main frame, hoeing devices on the hoeing frame, and means for operating the same, substantially as set forth.

8. A hoeing machine comprising a main 70 frame, a hoe provided with two sets of hoeing devices, one set being adjustable relative to the other in the direction of the axis of the hoe, and means for revolving the hoe at different speeds relative to the advance movement of the machine whereby the adjustment of the hoeing devices relative to each other may be utilized in securing any desired width of cut at the different speeds of the machine, substantially as set forth.

9. The combination in a hoeing machine, of a hoeing frame, a shaft therein for supporting the hoes, a plurality of sets of hoes, a plurality of arms or carriers for the hoes, the carrier for one set of hoes being adjustable in a 85 rotary direction on the shaft relative to the carrier for the other set whereby the distances between the hoes of one carrier and those of the other carrier may be varied and one of the hoe carriers being movable longitudinally along the shaft, and means on the hoeing frame for moving such carrier along the shaft, substantially as set forth.

10. A hoeing machine having a revolving hoe provided with two sets of hoeing devices, 95 one set being adjustable relatively to the other set in the direction of the axis of the hoe and means whereby such adjustment may be effected while the machine is in motion, substantially as set forth.

11. A hoeing machine having a revolving hoe provided with two sets of hoeing devices having carriers and blades, one of the blades of one set being adjustable on its carrier in the direction of travel of the machine and 105 one of the carriers being adjustable relative to the other carrier in the direction of motion of the machine while the machine is in motion, substantially as set forth.

12. A hoeing machine having a revolving 110 hoe comprising a carrier and a blade thereon, and a rake in advance of said blade and having a supporting device connected with the blade carrier.

13. In a hoeing device the combination 115 with a blade and a carrier therefor, of a rake in advance of the blade and having a bar adjustably connected with the blade carrier.

14. In a hoeing machine a revolving hoe provided with a blade and in advance thereof 120 with a rake revolving with the blade.

15. The combination of a main frame, a 125 hoeing frame, means supporting the rear end of the hoeing frame, a bar extending transversely of the main frame and having a track-way supporting the front end of the hoeing frame, and means for adjusting said bar relative to the main frame whereby to level the hoeing frame, substantially as set forth.

16. The combination with the main frame, 130

- a drive shaft and a carrier frame movable along and rocking on the drive shaft and having a forwardly projecting portion provided with bearings for a hoeing frame, a hoeing frame pivoted at its rear end at one edge in the forwardly projecting portion of the carrier frame, a block having a bearing for the front end of the hoeing frame, a bar pivoted at one end to the main frame and having a longitudinal trackway in which the said block travels, a lever pivoted to the main frame and having an arm connected with said trackway bar for adjusting the same relative to the main frame, a lever for shifting the carrier frame along the drive shaft, hoeing devices carried by the hoeing frame, and means for tilting the hoeing frame whereby to adjust the hoeing devices to any desired height from the ground, substantially as set forth. 5
17. The combination in a machine, substantially as described, of a carrier frame, a master wheel, a hoeing frame journaled to the carrier frame, a countershaft journaled in the hoeing frame and having an extension projecting into the carrier frame, a pinion on the countershaft and meshing with the master wheel, a pulley on the countershaft, a hoeing shaft journaled to the hoeing frame and provided with hoeing devices, a pulley on the hoeing shaft, and a belt connecting the pulley on the hoeing shaft with that on the countershaft, substantially as set forth. 10
18. The combination of a main frame, a drive shaft, a carrier frame rocking on the drive shaft, a hoeing frame pivoted to the carrier frame, a countershaft journaled to the hoeing frame, and geared with the master gear, a hoeing shaft, pulleys on the hoeing shaft and the countershaft, a belt connecting said pulleys, and a tightener operating upon the said belt, substantially as set forth. 15
19. A hoeing machine having a hoe comprising a blade, and a rake in advance of the blade and adjustable relatively thereto. 20
20. A machine comprising a main frame, a hoeing frame therein and pivoted at one edge in line with the direction of draft whereby its other edge may be raised and lowered, hoeing devices at such edge of the hoeing frame, means for shifting the hoeing frame laterally within the main frame, means for leveling the hoeing frame in the main frame, and means for tilting the hoeing frame whereby to raise and lower the hoeing devices. 55
21. A machine comprising a main frame, a drive shaft, a carrier frame rockable on the drive shaft, cultivating devices connected with the carrier frame, means for adjusting the cultivating devices relative to the carrier frame whereby they may be set to any desired position up or down independent of the rocking motion of the carrier frame, hoeing devices supported in the carrier frame, and means for adjusting the hoeing devices relative to the carrier frame whereby they may be set to different positions independent of the position of the carrier frame. 60
22. A hoeing machine having a revolving hoe provided with two sets of hoeing devices, one of the blades of one set being adjustable on its carrier in the direction of travel of the machine whereby it may be set rearwardly to double the space cut, substantially as and for the purpose set forth. 65
23. A hoeing machine having a revolving hoe comprising a shaft, two sets of hoeing devices thereon, one in rear of the other, one of the sets being adjustable along the shaft relatively to the other set and one of the blades of the rear set being adjustable in the direction of travel of the machine, whereby it may be set rearwardly to double the space cut, substantially as set forth. 70
24. A hoeing machine having a revolving hoe provided with two sets of hoeing devices, one set operating in rear of the other set and having one of its blades adjustable on its carrier in the direction of travel of the machine whereby it may be set rearwardly to double the width of space cut between cotton without change of gear, substantially as and for the purpose set forth. 75
